UNITED STATES PATENT OFFICE.

CLAUS CARLSON, OF HARTFORD, CONNECTICUT.

DESIGN FOR A SKATE.

SPECIFICATION forming part of Design No. 33,890, dated January 8, 1901.

Application filed December 14, 1900. Serial No. 39,932. Term of patent 7 years.

To all whom it may concern:

Be it known that I, CLAUS CARLSON, a citizen of the United States, residing at Hartford, in the county of Hartford and State of Connecticut, have invented and produced a new and original Design for a Skate, of which the following is a specification, reference being had to the accompanying drawings, forming part thereof.

Figure 1 is a view in side elevation of a skate, showing my new design. Fig. 2 is a top or plan view of the same.

As shown in the drawings, the leading or material feature of my design consists of a long and narrow body *a*, extending for a considerable distance beyond each end of an upward projection *b*, one end of the body being curved upward. The projection *b* is short

as compared with the body and is of a width equal to that of the body. On top of the projection is a flat portion *c*, round in form at each end, the side parts of the portion *c* curving inward toward each other at a point between the ends, and the nearest point of approach of these side parts being at or near the longitudinal center of the portion *c*.

Having described my invention, what I claim as new, and desire to secure by Letters Patent, is—

The design for a skate as herein shown and described.

CLAUS CARLSON.
